UNITED STATES PATENT OFFICE.

SAMUEL WULLSCHLEGER, OF BASLE, SWITZERLAND.

STRIPING MECHANISM FOR CIRCULAR-KNITTING MACHINES.

SPECIFICATION forming part of Letters Patent No. 463,432, dated November 17, 1891.

Application filed June 8, 1891. Serial No. 395,471. (No model.)

To all whom it may concern:

Be it known that I, SAMUEL WULLSCHLEGER, a citizen of the Republic of Switzerland, and a resident of Basle, in Switzerland, have 5 invented a new and useful Improvement in Striping Mechanism for Circular-Knitting Machines, of which the following is a specification, reference being made to the annexed drawings, in which—

10 Figure 1 is an elevation of a circular-knitting machine fitted with my improvement; Fig. 2, a plan thereof, with ribbing-cam shown in dotted lines and parts in section; Fig. 3, a side elevation of a part of the machine; Fig. 15 4, an elevation of another part; Fig. 5, a view showing the shape of the main thread-guide and latch-guard; Fig. 6, a view of the thread-guide and latch-guard as formerly used. Figs. 7 and 8 illustrate the formation of the fabric 20 on the ribbing-needles.

The object of the invention is to enable knitted goods having stripes running in the direction of length of the fabric to be made upon circular-knitting machines.

25 L L is the frame, carrying the vertical or frame needle-cylinder Z.

N is the frame cam-cylinder, which revolves around the needle-cylinder Z and is driven by beveled gear K from the shaft M in the 30 known manner. The ribbing-needle disk D is supported in the known manner upon the shaft D' of the ribbing-cam disk P, which is carried by the arm D² on the pillar D³. The frame C, attached to the cam-cylinder N, carries the main thread-bobbin S, the thread t of which is carried to the thread-guide Q upon the bracket R on the frame C.

To provide for the insertion of threads to form the stripes upon the fabric W at suitable 40 places along, upon the usual ring A, which retains the frame-needles and is located at the top of the cam-cylinder N, are placed pins for carrying the small reels or bobbins b for the respective threads. On the ring 45 A are also pillars c', carrying the rollers c, each adapted to revolve upon the pillar c', supporting it and arranged with its axis horizontal and in a radial line from the vertical axis X X of the machine. Each roller 50 carries the eccentrically-placed projecting tube r, through which the respective thread s is passed from the bobbin b. The roller c

has the flange or flanges c², for a purpose hereinafter shown. The ribbing-cams are revolved with the frame-cams by the arms B, 55 connected to the sleeve J on the shaft D', and brought into connection with the frame cam-cylinder N in the usual manner. The pin P' connects the cam-disk P to revolve with the arms B when the latter are driven with the 60 frame cam-cylinder N.

On one of the arms B is the sliding bar e, connected thereto by pins e' and slots e². On one of the pins e' is pivoted the latch d, having the turned-over end v, adapted to take 65 into a recess w in the sliding bar e and lock the same in its lowest position when desired. The tail of the latch d is connected to the tail of the plate e by the spring p, so that the same spring lifts the latch by drawing down 70 its tail, and lifts the sliding bar e into its highest position when not retained by the latch d. In this highest position of the sliding bar e the projection f thereon, which may be of leather, stands in a position where, during the revolution of the arm B, this projection f touches the lowest lying part of the flange or flanges c² of each wheel c, so that the wheel is revolved for an appreciable distance. On the frame C is a similar sliding 80 bar g, attached by pins and slots, and having the projection h of the same nature as the projection f, but intended to act upon the upper lying part of the flange or flanges c² of each wheel c, and thus act to revolve each 85 wheel in a direction contrary to the motion imparted by the projection f. The action of either one of these projections, as desired, will revolve the wheels c so as to bring the thread s, projecting from the tube r thereon, 90 into engagement with the latch of the ribbing-needle k, which stands opposite the tube r. By this means the respective ribbing-needle which has been pushed forward to receive the thread by means of the cams will receive 95 both the main thread t in the usual way and the stripe-thread s, the latter, however, lying in front of the former, so as to show upon the outside of the finished fabric. The other projection will operate to return the roller to its 100 first position, while the needle draws the loop and throws off the standing loop in the usual manner. The next rotation will again loop the respective thread s in the same manner

over the same needle, so that the second loop is formed in like manner. By successive rotations of the machine stripes are produced longitudinally with the fabric at or upon 5 those ribbing-needles which are respectively opposite the rollers *c*. By suitable arrangement or grouping of the rollers *c* various patterns of stripes may be produced.

Interrupted stripes may be produced by 10 setting the stripe mechanism out of action during the desired number of rounds by moving one or both projections *f h* out of action. The bar *g* is held out of action, when desired, by lifting the same and securing it in its upper position by screwing down the screws on 15 which it is guided.

I claim as my invention—

1. In a knitting-machine for the manufacture of knitted goods having longitudinal or 20 diagonal stripes or the like, the combination of a main thread-guide, a series of stationary auxiliary thread-guides located, as described, with regard to the needles on which the stripe or pattern stitches are to be knitted, a projection adapted to rock said auxiliary thread-guides, whereby their threads become engaged with the said needles, and a second projection adapted to return said auxiliary thread-guides to their original position, and 25

means for supporting the auxiliary thread- 30 guides and for supporting and actuating the main thread-guides and the two projections aforesaid, substantially as set forth.

2. A series of thread-guides consisting each of a wheel *c*, having a flange or flanges *c²* and 35 an eccentrically-placed thread-guide tube *r*, in combination with a projection adapted to rock said wheels in one direction, and a second projection adapted to return the said wheels to their first position, and means for 40 supporting said wheels *c* and for supporting and actuating the two said projections, substantially as and for the purpose set forth.

3. In a circular-knitting machine, a ring *A*, having pins for thread-spoils *b*, and thread-guides *c* thereon, located, as described, with regard to the needles on which the stripe or pattern stitches are to be knitted, in combination with the cam-cylinder provided with the bars *e* and *g*, having projections *f* and *h* 50 and rotating with the cams, substantially as and for the purpose set forth.

In witness whereof I have signed this specification in presence of two witnesses.

SAMUEL WULLSCHLEGER.
